UNITED STATES PATENT OFFICE.

JESSE S. WENTWORTH, OF NORWOOD, OHIO, ASSIGNOR TO THE HEEKIN CAN COMPANY,
OF CINCINNATI, OHIO, A CORPORATION OF OHIO.

CAN.

1,273,018.

Specification of Letters Patent. Patented July 16, 1918.

Application filed August 27, 1917. Serial No. 188,314.

To all whom it may concern:

Be it known that I, JESSE S. WENTWORTH, a citizen of the United States of America, and resident of Norwood, in the county of 5 Hamilton and State of Ohio, have invented new Improvements in Cans, of which the following is a specification.

The object of my invention is to provide a stable and non-leakable can, which may be 10 used as a substitute for the ordinary tin can, and in which a sheet metal is used, which is much thinner and less expensive than the metal used in tin cans.

In the accompanying drawings, in which 15 I have illustrated the preferred embodiment of my invention,

Figure 1 is a plan view of a strip of materials, which, when rolled, will form a can body embodying my invention.

20 Fig. 2 is a central sectional view of a can embodying my invention.

Fig. 3 is a similar view of a modified form of my invention.

Fig. 4 is a sectional view, taken upon line 25 4-4 of Fig. 2, of a part of a can body embodying my invention.

Fig. 5 is a sectional view of a part of a can body, taken upon line 5-5 of Fig. 3.

Heretofore in the manufacture of tin 30 cans, the sheet metal used has been of a gage, such that it has sufficient stability of itself to form the body of the can, and when, with the sheet metal, paper has been used, the latter has been simply a covering for 35 the former. Whereas, in my can, I use a sheet of metal, which is of so small a gage, that it has not sufficient stability alone to form a body for the can, and I impart the necessary stability by combining with this 40 mutable sheet metal, paper or other sheet material.

The sheet of metal which I use may be a fine wire screen, a thin perforated sheet metal, or a sheet metal of small or paper- 45 like gage, and indented at intervals.

The sheet material which gives stability to my sheet of metal, in the body of the can, consists preferably of a heavy fiber- paper, with unfinished surfaces, such as 50 wrapping paper.

The can may be lined interiorly and cov- 55 ered exteriorly with a woven paper, such as plated label paper, or, instead of such lining and covering, I may use a lining or cover- ing of lacquer, such, as for instance, a cobalt

lacquer, which, when baked to 300 degrees Fahrenheit, hardens.

Instead of this fiber-paper, I may use sheets of metal foil, such as tin foil or alu- 60 minium foil, to give stability to the sheet metal.

In the manufacture of my can, I prefer to roll up a strip of the materials into a cylindrical shape, to form the body of the can, first alining the sections of materials, in 65 the order which they are to occupy in the can body. For instance in Fig. 1, I have illustrated the order of arrangement where the can body is to have a lining 1 and a covering 2 of woven paper. Between sec- 70 tions 1 and 2, there is secured a section 3 of fiber paper. The ends of the sections are cut preferably at acute and obtuse angles to the edges thereof, so as to make an angular joint thereof in the can body. Instead of these 75 angular cuts at the ends, I may use an irregular cut, so as to avoid a right angle joint.

Section 1 is made of a length, such that its ends will overlap, when the strip is rolled, and will form the lining of the can body. 80 Section 3 is made preferably of a length, such that it will be rolled upon itself several times, when the strip is rolled. Section 2 is made of a length, such that its ends will overlap, and it will form the covering of the 85 can body.

A sheet metal section 4 is placed upon the inner surface of section 3, at a distance from section 1, such that the part of section 3, between the end of section 4 and section 90 1, will be equal to the periphery of the can. Section 4 is of a length such, that when rolled, its ends will overlap. To hold section 4 in place upon section 3, I may form pockets 5 and 6 for the corners thereof, by 95 pasting pieces of paper to strip 3 over said corners.

Before the strip of material is rolled, I 100 preferably apply to the inner surface there- of a layer of glue.

In instances where a lacquer finish is used in place of the woven paper lining 1 and cover 2, the lacquer may be applied either before or after the strip has been rolled. This lacquer finish is especially advan- 105 tageous for use upon cans, which are in- tended for holding acids. In some in- stances, I prefer to use the lacquer only upon that part of the strip which is to form the inside of the can. My can is one which is 110

adapted to take various kinds of finish, as for instance, instead of the lacquer finish, I may place an oil finish upon the inside of the can, and a dipped finish upon the exterior thereof.

While I prefer to place the strips of material in alinement with each other, and then to roll the strip upon cylindrical forms, to form the can body, I may roll the sheet metal, as for instance, the wire mesh, into a cylindrical form, and then dip it in bulk pulp and then compress the pulp firmly into and on the outside of the cylindrical wire mesh.

15 The bottom of the can may be formed either of a disk 7, made of layers of sheet metal and paper, such as illustrated and described in connection with Figs. 4 and 5, or may be made of a disk of sheet tin 8. In 20 Fig. 2, the disk 7 is shown as being secured to the can body by having its downturned end 9 rolled into the up-turned end 10 of the can body. In Fig. 3, the bottom 8 is

secured by up-turning its flange 11 around the lower end of the cylindrical body. The 25 open end of the can body may be finished by securing thereto the usual flanged end 12, which coöperates with the tapered top 13.

What I claim is:

1. A can, the body of which comprises a 30 cylinder of mutable metal, layers of fibrous paper covering the metal, and a lining and a cover for the fibrous paper.

2. A can, the body of which comprises a 35 cylinder of mutable metal, layers of fibrous paper covering the metal, and a lining and a cover of woven paper for the fibrous paper.

In testimony whereof, I have hereunto subscribed my name this 24th day of August, 1917.

JESSE S. WENTWORTH.
